UNITED STATES PATENT OFFICE.

JAMES M. CLAYTON, OF IOLA, KANSAS.

SEESAW.

1,193,994.

Specification of Letters Patent.

Patented Aug. 8, 1916.

Application filed October 21, 1914, Serial No. 867,863. Renewed March 16, 1916. Serial No. 84,700.

To all whom it may concern:

Be it known that I, JAMES M. CLAYTON, a citizen of the United States, residing at Iola, in the county of Allen, State of Kansas, have invented certain new and useful Improvements in Seesaws; and I do hereby declare the following to be a full, clear and exact description of the invention, such as will enable others skilled in the art to which it appertains to make and use the same.

5 This invention relates to improvements in see-saws.

One object of the invention is to provide a see-saw of simple and novel construction 15 which can be easily folded so as to be readily taken through a narrow space, such as a door-way.

Another object is to provide a see-saw in which the weight of more than one person at 20 one end can be readily compensated for at the other end.

A further object is to provide a see-saw in which the seats at the opposite ends will always maintain a horizontal position while 25 the see-saw is in motion.

25 Other objects and advantages will be apparent from the following description when taken in connection with the accompanying drawings.

30 In the drawings: Figure 1 is a side elevation of the see-saw at rest, Fig. 2 is a side elevation of the same in applied position, Fig. 3 is a top plan view in the position of Fig. 1, Fig. 4 is an end view, Fig. 5 is a vertical sectional view on the line 5—5 of Fig. 1, and Fig. 6 is an end view of the device in folded position.

35 Referring particularly to the accompanying drawing, there is a base which includes a strip 10 of suitable material, and the oppositely extending members 11, the latter being hinged to the upright 13 at opposite sides thereof. To the outer ends of the strip 10 are secured inclined braces 12, the inner ends 40 of which are suitably bolted to the vertical upright 13 which is secured centrally on the upper side of the said member 10. Hinged to the outer ends of the members 11 are inclined bars 14, the upper ends of which are

45 provided with pivoted slotted members 15 which receive staples 16 carried by the upright 13, cross keys 17 being passed through the staples after being received through the slots of the members 15. The upright 13 is

50 55 formed of two members between which are centrally pivoted the horizontal parallel

rocking beams 18 and 19, the former of which is disposed at the upper end of the upright while the lower is disposed just above the attaching points of the upper ends of the bars 12 and 14. The opposite ends of the beams 18 and 19 are equally spaced apart and pivotally connected together by the vertical links 20. These links are in pairs and have pivotally secured therebetween the seat 60 members 21. Secured to each side of the seat members 21 are the strips 22 to which are secured the transverse slats 23 forming the seats. Slidably mounted on one end of the upper beam 18 is a weight 24 which is 65 adapted to be shifted between the pivot of the said beam and the end. When one child occupies the seat at one end, and two children occupy the seat at the other end, this difference in weight must be compensated 70 for. This is done by sliding the weight 24 to different positions along the beam 18.

Pivotal secured on the end portions of the lower beam 19, inwardly of the connecting links 20 are foot-rests 25, these rests being adapted to be swung toward or away 80 from the links for children of different sizes. Secured on opposite sides of the upper ends of the links 20 are handles 26 which are 85 grasped by the occupants of the seats.

It will be noted that the seat supported members 21 are rigidly secured to the links 20 and extend outwardly therefrom at right angles. This causes the seats to remain in the horizontal position when the beams 18 90 and 19 are rocked on their pivots, the links 20 always maintaining a vertical or nearly vertical position.

When it is desired to move the see-saw, the same may be taken completely apart by 95 removing all of the bolts which connect the various parts, and by removing the cross keys 17, the bars 14 and base members 11 may be moved upwardly against the seats of the upright 13. In this connection it might 100 be well to mention that the bolts carry sleeves 27 so as to prevent wear on the holes of the openings through which the bolts pass.

When desiring to move the device through 105 a narrow place, such as a doorway, it is only necessary to move the members 11 and 14 on their hinges so that the entire device will be not much wider than the thickness of the beams 18 and 19.

110
What is claimed is:
A see-saw comprising a base including a

strip, a standard mounted on the center of said strip, laterally extending members, hinged to the lower end of the standard at opposite sides thereof, rigid braces secured 5 to the ends of the strip and to the support, braces hinged to the lateral members and detachably secured to the standard, a pair of horizontal and superposed parallel rocking beams mounted on the standard, link members pivotally connected to the ends of the 10 beams and spacing said beams apart, ad-

justable footrests carried by one of the beams, seats secured to the connecting links, and a shiftable weight carried between the upper beam of one side of the pivot thereof. 15

In testimony whereof, I affix my signature, in the presence of two witnesses.

JAMES M. CLAYTON.
